UNITED STATES PATENT OFFICE.

HENRY R. ROBERTS, OF NORTHWOOD, IOWA.

SPOUT FOR FLOUR-SIFTERS.

SPECIFICATION forming part of Letters Patent No. 701,936, dated June 10, 1902.

Application filed January 11, 1902. Serial No. 89,353. (No model.)

To all whom it may concern:

Be it known that I, HENRY R. ROBERTS, a citizen of the United States, residing at Northwood, in the county of Worth and State of 5 Iowa, have invented a new and useful Spout for Flour-Sifters, of which the following is a specification.

My invention relates to an improved spout for flour-sifters of that class employed in connection with gyratory bolts or plan-sifters; and the object of my invention is to provide an improved spout adapted for use both to convey material to or discharge the same from a plan-sifter and which spout is composed of 15 a plurality of non-collapsible metallic tubular sections and flexible joints, which connect the same together to adapt the sectional spout to conform to the motion of the plan-sifter; and my invention consists in the peculiar construction and combination of devices herein-after fully set forth and claimed.

In the accompanying drawings, Figure 1 is a perspective view of a portion of a plan-sifter or gyratory bolt provided with discharge-spouts embodying my improvements. Fig. 2 is a detail elevation of one of my improved spouts. Fig. 3 is a central sectional view of the same. Fig. 4 is a detail perspective view showing one of the flexible joints 30 of my improved spout, the parts thereof being separated.

In the construction of my improved sifter-spout I employ a plurality of metallic tubular sections 1, 2, and 3. The section 1 is the intake-section, the section 2 is the intermediate section, and the section 3 is the discharge-section. In practice the said sections are preferably of cylindrical form and the same may be of sheet-tin or any other suitable sheet 40 metal.

The sections 1 2 are connected together by a flexible joint 4, which comprises a pair of conical sections 5 6, the latter being inverted and the bases of the said sections 5 6 being secured together either by stitching them or in any other suitable manner. The section 5 is formed at its upper side with a collar 5^a of sufficient internal diameter to receive the lower end of the upper metallic tubular section 1. The section 6 is provided at its lower

side with a similar collar 6^a, which receives the upper end of the metallic tubular intermediate section 2. The flexible joint 7, which connects the intermediate tubular section 2 to the lower tubular section 3, is of the same 55 construction as the flexible joint 4. The sections of the said flexible joints or elbow members of the spout are preferably made of leather or other suitable flexible material. Rivets 8 on the collars of the flexible elbow-sections secure the same to the metallic tubular sections of the spout.

It will be understood that the elbow or joint members of my improved sifter-spout being composed of flexible material, as of leather, 65 and being of double conical form are flexible and are adapted to be bent in any direction, hence enabling the inflexible metallic tubular sections of my improved sifter-spout to be disposed at any angle with relation to 70 each other, and hence my improved sifter-spout is adapted to conform to the motion of the plan-sifter or gyratory bolt to which it is connected and as indicated in Fig. 3 of the drawings.

It will be understood that the tubular sections and flexible joint members of my improved sifter-spout are not liable to collapse while the plan-sifter or gyratory bolt is in operation, and thereby become choked. Hence 80 a serious objection to the flexible sifter-spouts heretofore employed is obviated. It will be furthermore understood that the metallic tubular sections and the flexible leather joint members of my improved sifter-spout are exceedingly durable and will not become speedily worn through by the scouring action of the material which passes through the spout. Hence my improved flour-sifter spout obviates another serious objection heretofore existing in spouts of this character.

Having thus described my invention, I claim—

1. A spout for flour-sifters, comprising a plurality of inflexible tubular sections, and 95 flexible joint members, of double conical form connecting the inflexible tubular sections together, substantially as described.

2. In a flour-sifter spout, the combination of a flexible joint member comprising a pair 100

of truncated conical sections of flexible material having their bases joined together and inflexible tubular sections having their ends secured to the truncated portions of the flexible sections, substantially as described.

3. In a flour-sifter spout, the combination of a flexible joint member comprising a pair of truncated conical sections of flexible material having their bases joined together and having their truncated portions provided with collars, and inflexible tubular sections having their ends secured in the said collars, substantially as described.

4. In a flour-sifter spout, the combination of a flexible joint member comprising a pair of truncated conical sections made of leather, having their bases joined together and provided at their truncated portions with collars, and inflexible tubular sections having

their ends secured in the said collars, substantially as described.

5. A flour-sifter spout comprising a plurality of inflexible tubular sections and flexible non-collapsible joint members to which the opposing ends of the inflexible tubular sections are attached, the said flexible non-collapsible joint members being of greater diameter than said tubular sections at points intermediate the ends of the latter, substantially as described.

In testimony that I claim the foregoing as my own I have hereto affixed my signature in the presence of two witnesses.

HENRY R. ROBERTS.
